COMBINED JACKET-HANDLE UNIT AND
WATER BOTTLE

Joseph H. Konefes, Libertyville, Ill., assignor to
Motor Products Corporation, Detroit, Mich., a
corporation of New York

Application March 12, 1951, Serial No. 14,463

Term of patent 14 years

(Cl. D58—26)

To all whom it may concern:

Be it known that I, Joseph H. Konefes, a citizen of the United States of America, residing at Libertyville, Lake County, Illinois, have invented a new, original, and ornamental Design for Combined Jacket-Handle Unit and Water Bottle, of which the following is a specification, reference being had therein to the accompanying drawing, forming a part thereof, wherein:

Figure 1 is a side elevation of a combined jacket-handle unit and water bottle showing my new design.

Figure 2 is a front elevational view of the combined jacket-handle unit and water bottle.

Figure 3 is a rear elevational view of the combined jacket-handle unit and water bottle.

Figure 4 is a top plan view of the combined jacket-handle unit and water bottle.

The dominant feature of my design resides in the portions shown in solid lines.

The side of the combined jacket-handle unit

and water bottle opposite that shown in Figure 1 is identical with the side illustrated in Figure 1.

I claim:

The ornamental design for a combined jacket-handle unit and water bottle, substantially as shown and described.

JOSEPH H. KONEFES.
